UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

MOUNTING FOR BOBBINS.

Application filed February 5, 1921. Serial No. 442,649.

To all whom it may concern:

Be it known that I, WALTER I. TUTTLE, a citizen of the United States, and a resident of Providence, county of Providence, and 5 State of Rhode Island, have invented an Improvement in Mountings for Bobbins, of which the following is a specification.

This invention relates to bobbin supporting mechanism and is more particularly 10 adapted for use in textile machinery. One of the objects is to provide mechanism of the above type of simple and practical construction and efficient action. Another object is to provide a mechanism of the above 15 type in which the parts are securely mounted and yet accurately positioned. Other objects will be in part obvious and in part pointed out hereinafter.

The invention accordingly consists in the 20 features of construction, combinations of elements and arrangement of parts which will be exemplified in the structure herein-after described and the scope of the application of which will be indicated in the following claims.

In the accompanying drawing in which is shown one of various possible embodiments of this invention,

Figure 1 is a longitudinal section thereof;

30 Figure 2 is an end view of the same; and

Figure 3 is a cross-section taken on the line 3—3 of Figure 1.

Similar reference characters refer to similar parts throughout the several views of the 35 drawings.

Referring now to Figure 1 of the drawings, there is shown at 10 a tubular support comprising an inner tubular member 11 formed of wood or the like surrounded by 40 an outer metal sleeve or sheath 12.

At one end of this support is provided a ring 13, the bore through which registers with that through the inner tube 11 and which is provided with three or more outwardly projecting lugs 14, the outer surfaces of each of which are flush with the outer surface of the sheath 12. These lugs fit in suitable slots at the end of the tube 12 as shown in Figure 2 of the drawings, and between the lugs the edge of the part 12 is flanged or headed over as shown at 15 to hold the parts securely in assembled relation.

At the opposite end of the support there is

provided a crown ratchet 16 flanged at 17 to 55 fit over and be secured to the sleeve 12.

The above tubular support 10 is adapted to fit removably within a bobbin, diagrammatically indicated at 18 which rests thereon and against the ratchet 16. There is a 60 likelihood however of substantial variation in the bore of bobbins and yet it has been found to be desirable that they be securely held in place and yet readily removable whatever their departure from uniformity. 65 Also it is highly desirable that they be centered with substantial accuracy with respect to the axis of the supporting member.

Turning now to the features of this invention which bear directly on the facts immediately above recited, there are provided a plurality of spring members 19 here shown as two in number, symmetrically disposed about the axis of the bobbin support. These springs which are of substantially identical 70 construction, may be formed of heavy spring wire bowed throughout their central portion and having their end parts 20 resting within slots in the member 11 to permit of slight longitudinal movement at one or both ends 75 as the spring is flattened out. The bowed portion of these springs passes through suitable slots in the outer sheath 12, which slots register with a recess or groove 21 in the member 11 into which the springs may be 80 compressed as they are flattened out and, if necessary, rest substantially flush with the outer surface of the tube.

Considering the action of one of these springs, it engages the bore of the bobbin with a yielding pressure, and even though the diameter of the latter vary, it will, while readily removable, be held in place with a substantially uniform friction. With a plurality of springs symmetrically disposed 90 they tend to hold the bobbin in co-axial position with respect to the tubular support. Even with the two springs shown, the bobbin is centered as regards the plane of the springs by their substantially equal and opposite resilient pressure and is centered as to 95 a plane transverse thereto by the tendency of the springs to find and retain the plane of maximum diameter of the bore of the bobbin.

100 It will thus be seen that there is provided apparatus in which the several objects of this invention are achieved and that the

same is of essentially simple and practical construction. The parts are readily assembled and yet securely held in position and act effectively to support a bobbin accurately 5 in position and yet permit its ready removal.

As various possible embodiments might be made of the above invention and as various changes might be made in the embodiment above set forth, it is to be understood 10 that all matter herein set forth or shown in the accompanying drawings is to be interpreted as illustrative and not in a limiting sense.

I claim as my invention:—

- 15 1. In mechanism of the class described, in combination with a bobbin or the like, a member adapted to enter the bore of the bobbin to support the same comprising an inner hollow wooden member and an outer metal sheath substantially encasing and permanently secured to said wooden member, said sheath having a longitudinal slot therein and said wooden member having a longitudinal groove registering with said slot and extending beyond each end of said slot whereby a recess is formed between said sheath and said inner member at each end of said slot, and an elongated spring member having its end slidably resting in said recesses and having its central portion tending to spring outwardly through said slot to press against the inner surface of the bobbin to prevent relative rotation between said bobbin and said supporting member.
- 20 2. In mechanism of the class described, in combination with a bobbin or the like, an

inner hollow supporting member having a plurality of longitudinal grooves formed in its surface, a metal sleeve member substantially encasing said inner supporting member and having a portion flanged over an end thereof to secure said two members together, said sleeve member having a plurality of longitudinal slots registering with said longitudinal grooves, a spring member seated in each of said grooves and tending at its central portion to spring outwardly through said slot against the inner surface of the bobbin to hold said bobbin in co-axial relation to said support and to prevent relative rotation between said bobbin and said support.

3. In mechanism of the class described, in combination with a bobbin or the like, a rotatable supporting member adapted to enter the bore of the bobbin and support the same to rotate therewith, said supporting member comprising an inner member having a plurality of grooves formed in its surface and an outer metallic sleeve substantially encasing said inner member and having a plurality of slots registering with said grooves, and a plurality of spring members resting in said grooves and pressing outwardly through said slots against the inner surface of said bobbin to prevent relative rotation between said bobbin and said support.

In testimony whereof, I have signed my name to this specification this 31st day of January, 1921.

WALTER I. TUTTLE.
